ANTIBURN DEVICE FOR WAVING SOLUTIONS IN PERMANENT WAVING

William A. Kunze, New York, N. Y.

Application February 27, 1936, Serial No. 65,949

12 Claims. (Cl. 132—36.1)

This invention relates to new and useful improvements in an anti-burn device for waving solutions in permanent waving.

It is customary in permanent waving to apply a waving lotion to wet the hair before heat is applied. It is generally known that unless great care is taken in the application of protective devices the chances of scalp burns are very great. In the past such burns were practically 100% attributed to the steam which is generated by the waving solution after heat is applied. I have found this to be true only in some cases. In most instances I have found that the waving solution itself is capable of burning the scalp without necessarily being turned into steam. This is particularly true with sensitive scalps.

In the past many varied types of apparatus have been applied to the hair and head during permanent waving to prevent generated steam from reaching the scalp. These devices have been negligent in preventing the waving solution from dripping on the scalp before the heat for permanent waving is applied. Consequently, many burns have resulted and the operators believed themselves at fault in not properly protecting the scalp from steam after the application of the heat.

This invention particularly proposes a device for drawing off dripping waving solution to prevent it reaching the scalp.

The invention has for an object the construction of a tube adapted to be associated with the protector for the roots of the hair and the scalp as generally used, and said tube to be characterized by the fact that it is provided with a perforated trough portion into which the waving solution may drip and from which it is sucked by air.

Still further the invention contemplates slightly altering the protector itself so as to direct the dripping of the waving solution at pre-determined points to guide it in reaching pre-determined points of the tube from which it is easy to draw it off.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a person with a permanent waving apparatus applied to the head protected from waving solution burns with a

device constructed according to this invention.

Fig. 2 is a perspective view of one of the protectors used in the permanent waving, shown bottom side up.

Fig. 3 is a fragmentary enlarged sectional view taken on the line 3—3 of Fig. 2.

Fig. 4 is a fragmentary sectional view taken on the line 4—4 of Fig. 3.

Fig. 5 is a sectional view of a different type of protector which is used in conjunction with spiral waving, to which the anti-waving solution burn device has been applied.

Fig. 6 is a plan view of Fig. 5.

In Fig. 1 a person 10 is illustrated with permanent hair waving apparatus 11 upon her head 15 connected with the electric cables 12 of a waving machine (not shown in detail on the drawing). In conjunction with the regular hair waving machine there is used a portable suction fan 13 from which a plurality of suction tubes 14 extend. 20 Each of these suction tubes connect with a tip member 15.

In Fig. 2 one of the protectors for the roots of the hair is shown. It comprises a pair of pivotally connected protector sections 16 which may be clamped on a lock of hair. The details of this protector are not given in this specification since they form no part of the invention. At the underside of the protector, at the junction of the section 16, there is a groove 17. Within this groove the tip member 15 extends.

The tip member 15 is formed with a longitudinally extending trough 18 formed with perforations 19 in its base. The base of the trough is formed into transverse ridges as clearly shown 35 in Fig. 4 forming a waved portion, and the perforations 19 are arranged at the low points of the ridges. The groove 17 is formed with a wavy base 17a varying in depth from the center towards the ends. This wavy contour is adapted 40 to fit into a corresponding wavy contour on the sides of the tip member 15 as clearly shown in Figs. 3 and 4. The relation of the parts is such that the low portions of the wavy contour 17a are superimposed upon the low portions of the 45 base of the trough 18.

Waving solution which may drip between the members 16 of the protector will run along to the lowest point of the wavy contour 17a. From these low points the drip will fall, and necessarily 50 must fall within the trough 18, and particularly, at a low portion of the base of the trough. The suction will draw the drip through the opening 19. It will then pass through the tube and be 55 discharged as moisture or vapor from the fan 13.

In Figs. 5 and 6 another form of the invention has been disclosed. According to this form, the anti-burn device is applied to the protector of a spiral type wave. The dot and dash lines 5 20 in Fig. 5, indicate a spiral wave former. At the base of this former there is a circular protector 21. This circular protector is formed with an opening 22 through which the drip may pass. A transverse opening 23 is formed in the 10 side of the protector 21 and communicates with the opening 22. The tip member 15 is inserted through the opening 23 so that the trough portion 18 and the perforations 19 are located beneath the opening 22.

15 While I have illustrated and described the preferred embodiments of my invention, it is to be understood that I do not limit myself to the precise constructions herein disclosed and the right is reserved to all changes and modifications 20 coming within the scope of the invention as defined in the appended claims.

Having thus described my invention what I claim as new and desire to secure by United States Letters Patent is:—

25 1. An anti-burn device for waving solutions for permanent hair waving, comprising a protector for the roots of the hair and having an opening beneath those portions likely to drip waving solution, a tube member having a tip portion extending into said opening and having perforations to receive said drip, and a suction device connected with said tube.

30 2. An anti-burn device for waving solutions for permanent hair waving, comprising a protector for the roots of the hair and having an opening beneath those portions likely to drip waving solution, a tube member having a tip portion extending into said opening and having perforations to receive said drip, and a suction 35 device connected with said tube, said protector including a pair of adjacent members, and said opening being in the form of a groove between said adjacent members.

40 3. An anti-burn device for waving solutions for permanent hair waving, comprising a protector for the roots of the hair and having an opening beneath those portions likely to drip waving solution, a tube member having a tip portion extending into said opening and having 45 perforations to receive said drip, and a suction device connected with said tube, said tube having a trough along its top face and said perforations being arranged in the base of said trough.

45 4. An anti-burn device for waving solutions for permanent hair waving, comprising a protector for the roots of the hair and having an opening beneath those portions likely to drip waving solution, a tube member having a tip portion extending into said opening and having 50 perforations to receive said drip, and a suction device connected with said tube, comprising a suction fan and a plurality of tubes connected therewith.

55 5. An anti-burn device for waving solutions for permanent hair waving, comprising a protector for the roots of the hair and having an opening beneath those portions likely to drip waving solution, a tube within said opening and having a trough portion to receive said drip, and a suction 60 device connected with said tube.

65 6. An anti-burn device for waving solutions for permanent hair waving, comprising a protector for the roots of the hair and having an opening beneath those portions likely to drip waving solution, a tube member having a tip portion 70 extending into said opening and having perforations to receive said drip, and a suction device connected with said tube, said opening in the protector extending from one side and connecting with a branch opening extending in from

75 opening beneath those portions likely to drip waving solution, a tube within said opening and having a trough portion to receive said drip, and apertures in the base of said trough, and a suction device connected with said tube, the base of said trough being formed with a wavy drain portion, and said apertures being in the low areas of said wavy formation. 5

7. An anti-burn device for waving solutions for permanent hair waving, comprising a protector for the roots of the hair and having an opening beneath those portions likely to drip waving solution, a tube within said opening and having a trough portion to receive said drip, and apertures in the base of said trough, and a suction device connected with said tube, the base of said trough being formed with a wavy drain portion, and said apertures being in the low areas of said wavy formation, the top wall of said drip portion being of wavy construction. 10 15 20

8. An anti-burn device for waving solutions for permanent hair waving, comprising a protector for the roots of the hair and having an opening beneath those portions likely to drip waving solution, a tube within said opening and having a 25 trough portion to receive said drip, and apertures in the base of said trough, and a suction device connected with said tube, the base of said trough being formed with a wavy drain portion, and said apertures being in the low areas of said 30 wavy formation, the top wall of said drip portion being of wavy construction, and the contacting wall of the tube being also of wavy construction feeding into said first mentioned wavy formation. 35

9. An anti-burn device for waving solutions for permanent hair waving, comprising a protector for the roots of the hair and having an opening beneath those portions likely to drip waving solution, a tube within said opening and having a trough portion to receive said drip, and apertures in the base of said trough, and a suction device connected with said tube, the base of said trough being formed with a wavy drain portion, and said apertures being in the low areas of 45 said wavy formation, the top wall of said drip portion being of wavy construction, and the contacting wall of the tube being also of wavy construction feeding into said first mentioned wavy formation, and the low portions of the 50 wavy formation of the top wall of the opening for the drip being aligned with the low portions in the trough. 40 45 50

10. An anti-burn device for waving solutions for permanent hair waving, comprising a protector for the roots of the hair and having an opening beneath those portions likely to drip waving solution, a tube member having a tip portion extending into said opening and having perforations to receive said drip, and a suction device 55 connected with said tube, said opening in the protector extending from one side and connecting with a branch opening extending in from the top. 60

11. An anti-burn device for waving solutions for permanent hair waving, comprising a protector for the roots of the hair and having an opening beneath those portions likely to drip waving solution, a tube member having a tip portion 65 extending into said opening and having perforations to receive said drip, and a suction device connected with said tube, said opening in the protector extending from one side and connecting with a branch opening extending in from 70 75

2,081,882

the top, said tube being extendable into said side opening.

12. An anti-burn device for waving solutions for permanent hair waving, comprising a protector for the roots of the hair and having an opening beneath those portions likely to drip waving solution, a tube member having a tip portion extending into said opening and having perfora-

tions to receive said drip, and a suction device connected with said tube, said opening in the protector extending from one side and connecting with a branch opening extending in from the top, said tip member being extendable into said side opening and having a trough portion in the top into which the drip may enter.
